SPRING ACTUATED SHAVER

Georges Monnet, New York, N. Y.

Application March 5, 1957, Serial No. 45,115

Term of patent 3½ years

(Cl. D22—3)

Fig. 1

Fig. 2

The side opposite to that of Figure 2 is similar in appearance to that shown in Figure 2.

I claim:

The ornamental design for a spring actuated shaver, as shown and described.
